[57] **CLAIM**

The ornamental design for a miniaturized maple syrup container, as shown and described.

DESCRIPTION

FIG. 1 is a perspective view of a miniaturized maple syrup container showing my new design;

FIG. 2 is a perspective view thereof, with the hinged top portion in an open position;

FIG. 3 is a top plan view thereof, with the hinged top portion in a closed position;

FIG. 4 is a front elevation view thereof;

FIG. 5 is a right side elevation view thereof;

FIG. 6 is a left side elevation view thereof;

FIG. 7 is a bottom plan view thereof;

FIG. 8 is a rear elevation view thereof;

FIG. 9 is a top plan view thereof, with the hinged top portion in an open position; and,

FIG. 10 is a perspective view thereof, with the hinged top portion in an open position and rotated 180 degrees.
